UNITED STATES PATENT OFFICE

ALOIS JAYET, OF YVERDON, SWITZERLAND, ASSIGNOR TO LECLANCHE S. A., OF YVERDON, SWITZERLAND

ELECTRICAL CONDENSER

Application filed February 10, 1928, Serial No. 253,447, and in Germany February 12, 1927.

The present invention relates to electrical condensers.

It has been proposed to form the terminals of small condensers with lamellæ made of flexible thin metal plates imbedded in an insulating substance and to guard the same against mechanical stresses in such a manner, that in ordinary use the terminals cannot get loose and no air can get to the dielectric so that the capacity of the condenser cannot diminish. Hitherto it was difficult to shut off these insulating pieces air-tight with the usual sheet metal casing of the condenser, because these pieces could not be heated again after their finishing in order to get united with the sheet metal casing. The casting of the dielectric was very irregular since it happened that, while the terminals and the insulating pieces supported great stresses, the connection between the insulating piece and the sheet metal casing formed a weak part which gave way under such stresses. Another method was by filling-up the cover while simultaneously catching the same under a flange of the casing. In this case the insulating material could never get dry enough so as to afford a solid hold to the sheet metal plates.

The object of the invention is a condenser of the kind described in which the body of insulating material wherein the lamellæ used as terminals are imbedded is surrounded by a sheet-iron frame which is attached air-tightly to the sheet metal casing by soldering.

In the annexed drawings a condenser is represented as an example and constructed according to the present invention.

Fig. 1 shows the apparatus in an unfinished state with lifted cover in the position in which the terminals are soldered to the armature of the condenser.

Fig. 2 is a top view of the condenser.

Fig. 3 is a section on line IV—IV in Fig. 2.

Fig. 4 a section on line III—III in Fig. 2 and

Fig. 5 a view of a terminal having a corrugation.

a designates the casing of the condenser.

It is, as is usual made of sheet metal and con-

tains two armatures not represented and cast into an insulating substance *b*. The armatures project with lugs *c* serving as connections between the armatures and the terminals *d* leading from the insulating substance. The terminals are formed like thin plates of sheet copper and corrugated about at the midst of their length. These terminals are imbedded, together with a sheet metal frame *e* into an insulating body *f*. This insulating body is rigid and heat-resisting and forms in combination with the terminals and the sheet-metal frame a cover for the casing. On the bottom side of this cover the protruding ends of the terminals are bent over, thus forming surfaces to which the lugs coming from the armature are soldered with a drop of solder, in the position as represented in Fig. 1. After this has been done the cover is pressed down into the mouth of the casing and the upper part of the body is surrounded with an apertured piece of sheet metal *g*, whereupon the piece *g* together with the frame *e* are soldered to the edge of the casing. In this manner the armatures are enclosed air-tightly within the casing and under normal conditions no humidity can find access to the armatures.

What I claim as new is:

In an electrical condenser, an outer-casing, a dielectric filling as means for insulating the armatures and reaching up near to the border of the casing, two slender lugs forming the connecting means of the armatures and extended over the surface of said filling, a cover for the casing, comprising a central insulating body, terminals imbedded therein with a corrugated portion and having portions projecting from the bottom of the central body and soldered to said slender lugs and a sheet-metal frame embedded into said central body and fitting inside the walls of the upper free space of the casing and soldered thereto so as to form an air and watertight joint.

In testimony whereof I affix my signature.

ALOIS JAYET.
